UNITED STATES PATENT OFFICE.

JOHN J. WHARAM, OF DETROIT, MICHIGAN, ASSIGNOR TO FORD MOTOR COMPANY, OF HIGHLAND PARK, MICHIGAN, A CORPORATION OF DELAWARE

RADIATOR-ORNAMENT MOUNTING.

Application filed August 24, 1927. Serial No. 215,170.

The object of my invention is to provide a radiator ornament mounting of simple, durable and inexpensive construction.

Still a further object of my invention is to provide a mounting for a radiator ornament such that the ornament will always necessarily be returned to position with its axis parallel to the longitudinal axis of the car whenever the radiator cap has been opened for any reason, and to provide means whereby the liquid seal between the radiator cap and the filler neck may be insured.

Still a further object of my invention is to mount a radiator ornament on a hinge of the concealed type within the radiator filler neck so that the radiator ornament and cap may be swung back off of the filler neck out of the way but the ornament will always be returned to a predetermined position.

Still a further object of my invention, is to provide a radiator ornament which is mounted on a concealed hinge fastened within the radiator filler neck, and to provide a skirt or sleeve in connection with said radiator ornament which may tighten the radiator ornament onto the filler neck to hold it in position, and at the same time a liquid seal may be secured between the filler neck and the ornament without, however, varying the predetermined position of the radiator ornament whenever the cap is in closed position.

Still a further object of my invention is to provide means for locking the radiator ornament on such a cap in such a way that it will be difficult to remove same without taking a considerable period of time.

With these and other objects in view, my invention consists in the arrangement, combination, and construction of the various parts of my improved device, as described in the specification, claimed in the claims, and illustrated in the accompanying drawings, in which:

Figure 1 shows a vertical central sectional view of my improved device, the radiator cap being shown in its open position.

Figure 2 shows a similar view with the cap shown in its closed position.

Figure 3 shows a horizontal sectional view taken on the line 3—3 of Figure 1.

Figure 4 shows a vertical transverse central sectional view taken on the line 4—4 of Figure 1, and

Figure 5 shows an enlarged detail elevation of the screw device used for securing the radiator ornament to the radiator cap.

Referring to the accompanying drawings, I have used the reference numeral 10 to indicate generally a radiator shell for radiator, (not shown) having the filler neck 11. This filler neck is provided with the usual threads 12 at the top thereof whereby a radiator cap may be secured thereto. Spaced bosses 13 and 14 are preferably formed integral within the radiator filler neck near each side thereof and near the back thereof. Aligned longitudinal horizontal openings 15 are formed in these bosses 13 and 14 to receive a pintle pin 16. This pintle pin is secured in place in the bosses by filling the ends of the openings 15 with solder 17 or any suitable material so that the filler neck may be smoothed off and nickel plated over the ends of these openings 15 and the location of said openings will not be apparent. A link 18 is pivotally mounted at one end on the pintle pin 16 between the inner ends of the bosses 13 and 14. This link 18 is of less length than the diameter of the radiator filler neck 11 near the upper end thereof. A slot 19 is formed in the free end 75 of the link 18 and receives a pin 20.

A disc 21 is pivotally mounted on the pin 20 by means of a member having the clevis 22 and the shank 23, the latter being riveted at 23A into the disc 21 to make this clevis member rigid with a disc 21. The clevis 22 has countersunk portions adjacent to the aligned openings in the ends thereof as is indicated at 37 in Figure 4, so that when the ends of the pin 20 are riveted over into the counter sunk portions 37 it will be necessary to file or grind off most of the clevis 22 before enough of the riveted over portions of the pin 20 can be removed to drive the pin 20 out of the clevis.

I have herewith illustrated a radiator ornament comprising the image of a greyhound which I have designated generally by the reference numeral 24, this greyhound being either permanently secured to or formed integral with a base member 25. This base member forms the top of the radiator cap and the support for the greyhound, and is provided with central depending bosses 26 designed to receive screws 27 which also pass through the disc 21 whereby the base may be fastened to that disc.

These screws 27 are illustrated in detail in Figure 5, wherein it will be noted that they have a stove bolt head 28, which however lacks the usual screw driver engaging slot. Instead the screw 27 is provided with an extension 29 having the screw driver slot 30 therein. The place where this extension 29 connects to the head 28 is contracted so that when the screw 27 has been screwed into the base 25 through the plate 21 then this extension 29 may be hit a sharp blow to knock it off from the screw 27. This makes it substantially impossible to unscrew the screw 27 by any ordinary means after the extension 29 has been knocked off, hence unauthorized removal of the radiator ornament 24 is largely eliminated. Unauthorized removal is further rendered difficult by making a prick punch 38 at the edge of the head 28. From the construction of the parts heretofore described, it will be seen that the radiator ornament 24 may be swung up on the double or concealed hinge which has been described so that it will reach the position indicated in Figure 1. When it is in this position the cap does not interfere with filling the radiator but when then the cap is replaced on the filler neck it will be seen that this construction insures that the radiator ornament will be in a predetermined position. For instance, in connection with the image shown, a greyhound, the axis of the image will always be parallel with the axis of the car.

A skirt or sleeve 31 is provided with a knurled portion 32 whereby it may be readily rotated by hand. The lower part of sleeve 32 is internally threaded as at 33 to co-act with the threads 12 of the radiator filler neck 11. The upper end of the sleeve 31 is provided with an inwardly extending annular flange 34 which is designed to extend between the disc 21 and a similar downwardly extending flange 35 of the base 25, whereby the sleeve 31 may rotate freely relative to the base and disc, but axial movement thereof is prevented. A compressible gasket 36 is disposed below the disc 21 so that when the sleeve 31 is screwed on to the filler neck, the gasket 36 will be compressed between the disc 21 and the top of the filler neck to form a liquid tight joint therebetween. The flange 34 engages the sleeve 31 to draw the disc 21 down against the filler neck when said sleeve is rotated with the threads 12 in engagement with the threads 33.

The advantages of my improved radiator ornament mounting have been pointed out in the course of the specification, but it may be well to again point out that the principal advantage is that the radiator ornament is al-

ways returned to a predetermined position when the cap is in closed position.

Still a further advantage results from the fact that the liquid joint between the cap and the filler neck is readily secured by this construction. Unauthorized removal of the ornament is rendered extremely difficult, in some three ways. The base 25 which carries the ornament can hardly be removed without drilling out the screw 27 from the disc 21 which is a tedious operation. The pin 20 cannot be driven out from the clevis 22 without practically destroying the usefulness of that clevis. The pin 16 cannot be driven out from the opening 15 until the solder 17 has been both located and removed. In other words the entire structure has been protected at all of the exposed points in such a way that unauthorized removal thereof is either delayed or made unprofitable.

Some changes may be made in the construction and combination of the various parts of my improved device without departing from the spirit of my invention, and it is my intention to cover by my claims such changes as may reasonably be included within the scope thereof.

I claim as my invention:

1. In a device of the character described, a neck member, a base member hingedly connected to said neck member, and a sleeve member having rotary engagement with the base and screw engagement with the filler neck whereby said sleeve may serve to insure a liquid tight joint between the filler neck and the base while the hinge connection may insure a predetermined position of the base when the latter is in its closed position.

2. In a device of the character described, a base member designed to receive an ornament, a filler neck, a sleeve member, means for operatively connecting the base member with the filler neck to permit the latter to be swung away therefrom on a hinge connection, and means operatively connecting the base and filler neck and the sleeve to draw the base down onto the filler neck to form a liquid tight connection therewith.

3. In a device of the character described, a filler neck, a base member, a concealed hinge structure operatively connecting the base member with the filler neck, and a sleeve rotatably mounted on the base member and having threaded engagement with the filler neck whereby the base when in closed position will be in a predetermined position relative to the filler neck and a liquid tight joint may be formed between the base and the filler neck.

JOHN J. WHARAM.
